(57) **CLAIM**

The ornamental design for an electric shaver, as shown and described.

DESCRIPTION

FIG. 1 is a top front perspective view of a dry shaver showing my design

FIG. 2 is a front view of FIG. 1

FIG. 3 is a side view of FIG. 1

FIG. 4 is a side view of FIG. 1

FIG. 5 is a rear view of FIG. 1

FIG. 6 is a top plan view of FIG. 1

FIG. 7 is a bottom plan view of FIG. 1

FIG. 8 is a front view showing my design inverted with respect to FIGS. 1-7 and with the cover rotated 180 degrees to expose the shaver head

FIG. 9 is a rear view showing my design inverted with respect to FIGS. 1-7 and with the cover rotated 180 degrees to expose the shaver head; and,

FIG. 10 is a front view showing my design inverted with respect to FIGS. 8+9 and with the cover rotated 45 degrees to expose the shaver head.

The broken lines are shown for illustrative purposes only and form no part of the claimed design.
